US0D1068806S

(12) **United States Design Patent** (10) **Patent No.:** **US D1,068,806 S**
(45) **Date of Patent:** **** Apr. 1, 2025**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Alfred B. Huergo Wagner**, Redwood City, CA (US); **Richard D. Lyons**, London (GB); **William A. Sorrentino, III**, Mill Valley, CA (US)

(73) Assignee: **Apple Inc.**, Cupertino, CA (US)

(**) Term: **15 Years**

(21) Appl. No.: **29/877,241**

(22) Filed: **Jun. 4, 2023**

(51) **LOC (15) Cl.** **14-04**

(52) **U.S. Cl.**

(57) **CLAIM**

The ornamental design for a display screen or portion thereof with graphical user interface as shown and described.

DESCRIPTION

The FIGURE is a front view of a display screen or portion thereof with graphical user interface showing the claimed design.

The outer peripheral dot-dashed broken lines in the FIGURE show a display screen or portion thereof, and form no part of the claimed design.

The inner peripheral dashed broken lines in the FIGURE show a boundary or portions of the graphical user interface that form no part of the claimed design. The other dashed broken lines in the FIGURE show portions of the graphical user interface that form no part of the claimed design.

1 Claim, 1 Drawing Sheet
